FIG. 4

UNITED STATES PATENT OFFICE.

THOMAS ELSUM, OF NEWARK, NEW JERSEY.

SKATE-RUNNER SHARPENER.

1,022,665.

Specification of Letters Patent.

Patented Apr. 9, 1912.

Application filed June 6, 1911. Serial No. 631,617.

To all whom it may concern:

Be it known that I, THOMAS ELSUM, a citizen of the United States, residing at Newark, in the county of Essex and State 5 of New Jersey, have invented certain new and useful Improvements in Skate-Runner Sharpeners; and I do hereby declare the following to be a full, clear, and exact description of the invention, such as will 10 enable others skilled in the art to which it appertains to make and use the same, reference being had to the accompanying drawings, and to characters of reference marked thereon, which form a part of this specification. 15

The present invention relates, generally, to improvements in sharpening tools; and, the invention has reference, more particularly, to a novel construction of skate-sharpener. 20

The present invention has for its principal object to provide a simple, cheap, and efficient device for sharpening the runners of skates, and similar articles, the same comprising a means for burnishing and turning the edges of skate-runners, and the like, to provide the same with properly sharpened edges, so that the runner will properly cut into the ice in a manner to prevent lateral 25 slipping or sliding of the skate.

With the various objects of this invention in view, the said invention consists, primarily, in the novel construction of skate-sharpener hereinafter set forth.

The invention is clearly illustrated in the accompanying drawings, in which:—

Figure 1 is the side elevation of a skate, illustrating in connection therewith, the novel construction of skate-sharpener and the manner of applying the same to the 40 skate-runner to sharpen the latter. Fig. 2 is a large detail transverse section of the skate-runner, with the novel construction of skate-sharpener applied thereto, and illustrating the manner of performing its sharpening function. Fig. 3 is a large detail cross-section of the same, said section being taken on line 3—3 in said Fig. 2. Fig. 4 is a central longitudinal section of the said 45 sharpening device, the same being removed from the skate-runner.

Similar characters of reference are employed in all of the hereinabove described views, to indicate corresponding parts.

Referring now to the said drawings, the

reference-character 1 indicates a skate provided with the usual skate-runner 2.

The reference-character 3 indicates the novel construction of skate-sharpener made according to and embodying the principles 50 of the present invention, the same comprising a body-portion 4 forming a handle which is provided with a rectangular opening 5 which constitutes a key or wrench adapted to be applied to the squared heads 6 of the 55 skate clamp-operating screws 7, to manipulate the respective clamp-devices 8, as will be clearly evident. Connected with the said body-portion 4 of the skate-sharpener and key 3 is a bifurcated head 9, the same providing a V-shaped opening 10, and the edges of which are preferably curved or rounded, so as to provide the burnishing or sharpening surfaces 11. Said bifurcated head 9 is further provided with guide-fingers or 75 projections 12 which turn inwardly toward each other, and which are located at the opening or mouth of said V-shaped opening 10.

The manner of using the novel skate-sharpener is as follows: The bifurcated head 9 is slipped or slid upon the skate-runner 2, so that the edge of the runner 2 is registered within and engaged by the burnishing or sharpening surfaces 11 of said V-shaped opening 10, while, at the same time, said guide-fingers or projections 12 engage the sides of the body of said skate-runner 2, in the manner shown in Fig. 2 of the drawings, thereby preventing any lateral movement of the device and maintaining the burnishing or sharpening surfaces 11 in proper relation to the respective bottom edges of the skate-runner. The skate-sharpener is then drawn longitudinally along the 85 length of the skate-runner, while at the same time, the operator exerts a firm pressure upon the tool to maintain the burnishing or sharpening surfaces 11 in their operative contact with the skate-runner. As 90 said burnishing or sharpening surfaces 11 are thus drawn along the skate-runner, they remove any outwardly projecting curl or edge from the runner, and tend to turn inwardly and toward each other the respective 95 edges of the runner, thereby producing the inwardly turned or projecting sharp edges 13, as shown in Fig. 2 of the drawings, and thereby providing a means whereby the 100 skate-runner is caused to firmly grip the ice 110

and move longitudinally upon the surface thereof, without any tendency to lateral slipping or sliding. The guide-fingers or projections 12, in their engagement with the sides of said skate runner, maintain the position of said V-shaped opening 10, and the burnishing or sharpening surfaces provided thereby, with relation to the runner of the skate, whereby the edges of said skate-runner are turned and sharpened in a uniform manner, so that the same are properly alined and are properly paralleled with each other; and, furthermore, no slipping of the tool is possible during the sharpening operation, whereby any gouging or nicking of the edges of the skate-runner is prevented.

It will be understood, that my present invention provides a very simple and effective tool for the purpose hereinabove stated, and one which can be easily and quickly operated to maintain in good condition the skate-runner, maintaining its so called "hol-

low ground" condition much longer than can otherwise be done.

I claim:—

1. A skate-sharpener comprising a body-portion provided with a bifurcated head forming a substantially V-shaped opening providing burnishing or sharpening surfaces, and a pair of guide-fingers or projections located at the mouth of said V-shaped opening. 25

2. A skate-sharpener comprising a body-portion provided with a bifurcated head forming a substantially V-shaped opening 30 35 providing burnishing or sharpening surfaces.

In testimony, that I claim the invention set forth above I have hereunto set my hand this 27th day of May, 1911.

THOMAS ELSUM.
